UNITED STATES PATENT OFFICE

FRANK J. KINCAID, OF CHARLESTON, WEST VIRGINIA, ASSIGNOR TO LIBBEY-OWENS-FORD GLASS COMPANY, OF TOLEDO, OHIO, A CORPORATION OF OHIO

SHEET GLASS APPARATUS

Application filed November 15, 1930. Serial No. 495,810.

The present invention relates to apparatus for producing sheet glass.

In the well-known system for drawing sheet glass as exemplified in the patent to 5 Colburn, No. 1,248,809, granted December 4, 1917, the bending roll about which the sheet is deflected from the vertical into the horizontal is ordinarily mounted to rotate freely with the sheet and is driven thereby so that 10 it will move at the same speed as the draw of the sheet to prevent relative movement therebetween. Due to various reasons, however, the even and uniform rotation of the bending roll is sometimes prevented, as a 15 consequence of which the said roll may rotate in a rather jerky or uneven fashion. When this temporary retarding of the bending roll occurs, a relative movement between the sheet and roll is had which is an undesirable condition since it tends to injuriously affect the thickness and flatness of the sheet produced. 20 As an example, one of the reasons or factors which may tend to prevent free rotation of the bending roll is the binding of the said 25 roll in its supporting bearings.

The principle aim and object of this invention is to overcome the above objectionable features by the provision of means associated with the bending roll which will at 30 all times insure the free, even and uniform rotation thereof.

Another object of the invention is the provision of braking means associated with the bending roll in a manner to apply a constant 35 braking or retarding force thereto, as a result of which the rotation of the roll will remain steady and uniform.

Other objects and advantages of the invention will become more apparent during 40 the course of the following description when taken in connection with the accompanying drawings.

In the drawings forming a part of this 45 application and wherein like numerals are employed to designate like parts throughout the same,

Fig. 1 is an elevation of apparatus provided by the present invention,

50 Fig. 2 is a vertical longitudinal section

taken substantially on line 2—2 of Fig. 1, and

Fig. 3 is a section taken substantially on line 3—3 of Fig. 2.

Although the present invention has been 55 illustrated and will be hereinafter described in connection with a Colburn machine for drawing sheet glass, yet it is to be understood that it is not limited to use in such connection but may be employed to advantage in various 60 other types of sheet glass forming machines.

In the Colburn machine, however, a glass sheet 5 is drawn upwardly in flat sheet form from a bath of molten glass 6 contained in a working receptacle or draw pot 7, the glass 65 being preferably supplied to the receptacle from a suitable continuous tank furnace. Knurled edge engaging rollers 8 are also preferably provided to maintain the sheet to width and are arranged closely adjacent the 70 meniscus 9. The sheet 5 is drawn in a vertical plane for a suitable distance, after which it is passed over a bending member or roll 10 to deflect the sheet from the vertical into a horizontal plane. The sheet then passes 75 horizontally over the bending roll 10 and idler roll 11 on through a combined drawing and flattening mechanism (not shown) into an annealing leir.

The bending roll 10 is mounted to freely 80 rotate with the sheet 5 and is driven thereby so that it will rotate at the same speed as the draw of the sheet to prevent relative movement therebetween. The idler roll 11 is adapted to support the sheet between the 85 bending roll 10 and the drawing and flattening mechanism and, although this roll is known in the art as an idler roll because of its use, it is nevertheless positively driven.

The bending roll 10 is supported adjacent 90 each end in a bearing bracket 12 by means of a bearing 13 carried in a cage 14 which includes a rounded portion 15 seated in a groove 16 formed in the bracket 12 so that the bending roll can automatically align itself. 95 The bearing bracket 12 is preferably pivotally carried at the lower end of a vertical hanger rod 17 upon a pin or trunnions 18. A combined flame and thrust guard 19 is carried by the bending member 10 to protect 100

the bearing 13 and associated parts from the flame and heat used in softening the sheet when it is being deflected over said roll, and which also receives the thrust upon any longitudinal movement of the bending roll within its bearings.

Although the bending roll is preferably mounted to freely rotate with the sheet, it oftentimes will fail to rotate, due to various reasons and, as a consequence, the sheet has separated from its source, thus making it necessary to start a new sheet over again. It is therefore desirable that means be provided for positively rotating the bending roll when the speed thereof drops beneath a certain point. This may be taken care of automatically, if desired, by the provision of an overrunning or one-way clutch associated with the bending roll as disclosed in the patent to L. D. Blackshire et al., No. 1,614,098, issued January 11, 1927, or by the use of a manually operated clutch such as illustrated in the drawings. Thus, there is keyed to either one or both ends of bending roll 10 a sleeve 20, and freely mounted upon this sleeve is a sleeve bearing 21 carrying a sprocket 22 and being provided at its outer end with a series of teeth 23. Slidably keyed upon sleeve 20 outwardly of sleeve bearing 21 is a slidable clutch section 24 provided with teeth 25 adapted to mesh with teeth 23 on bearing sleeve 21. The bearing sleeve normally rotates freely upon sleeve 20 and the clutch section 24 is maintained out of engagement therewith. However, when the rotation of the bending roll ceases or drops beneath a certain predetermined point, an operator can throw the clutch section 24 into engagement with bearing sleeve 21, whereupon the rotation of the sprocket 22 will be imparted to the bending roll through clutch section 24.

Trained about the sprocket 22 is a sprocket chain 26 also trained about a sprocket 27 keyed to the corresponding end of idler roll 45 11. This idler roll carries a second sprocket (not shown) about which is trained sprocket chain 28 driven from a suitable source of power.

As pointed out above, there are certain factors, such as the binding of the bending roll within its bearings, which sometimes tend to temporarily retard the free rotation of the said roll by the sheet being drawn and which results in the bending roll being rotated in a rather jerky and ununiform fashion. This is of course an undesirable condition since it tends to injuriously affect the proper formation of the sheet. However, according to the present invention, this objectionable feature is avoided by the provision of means associated with the bending roll and exerting a constant braking or retarding action thereupon. To this end, there is secured to sleeve 20 by means of bolts or the like 29 a collar 30. Encircling this collar are the semi-circular

brake bands 31 and 32 having at one end ears 33 which are secured together by a bolt 34 and nut 35. The opposite ends of the brake bands 31 and 32 are provided with offset end portions 36, and bearing against the outer side of each of these offset portions is a compression spring 37 tending to normally urge the brake bands inwardly toward one another and into engagement with the collar 30. One end of the compression spring 37 bears against the offset end portion 36 and the opposite end against a cup member 38 which is contained within a housing 39 carried by a bracket 40 secured to the bearing bracket 12. Passing through the housing 39 is an adjusting element 41, the inner end of which engages cup member 38 so that, upon rotation of the adjusting element 41, the force of the springs 37 can be varied to regulate the pressure of the brake bands upon the collar 31 and consequently the braking or retarding force exerted upon the bending roll. The resistance offered by the friction brake just described to the free rotation of bending roll 10 is adapted to be greater than any one or all of those variable factors which might tend to temporarily retard the rotation thereof, as a result of which the rotation of the said roll will not be affected thereby or, in fact, by any retarding force offering a less resistance than the brake. The bending roll will therefore be caused to rotate in a steady, uniform manner at all times. This invention is now in actual use with very satisfactory results.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In apparatus for forming sheet glass, freely rotatable means for deflecting a semi-plastic sheet of glass from one plane into another, means for rotatably supporting said first-mentioned means, and means associated with said rotatable means for resisting the free rotation thereof. 110
2. In apparatus for forming sheet glass, a freely rotatable roll for deflecting a semi-plastic sheet of glass from one plane into another, means for rotatably supporting said roll adjacent its opposite ends, and a breaking mean associated with said roll for retarding the free rotation thereof. 120
3. In apparatus for forming sheet glass, a freely rotatable roll for deflecting a semi-plastic sheet of glass from one plane into another, means for rotatably supporting said roll adjacent its opposite ends, and a friction brake mounted upon said roll for resisting the free rotation thereof. 123 130

4. In apparatus for forming sheet glass, means for drawing the sheet upwardly, rotatable means for deflecting the sheet from a substantially vertical plane into a substantially horizontal plane, said means being driven by the sheet passing thereover, means for rotatably supporting said first-mentioned means, and means associated with said deflecting means for resisting the free rotation thereof.

5. In apparatus for forming sheet glass, means for drawing the sheet upwardly, a freely rotatable roll for deflecting the sheet from a substantially vertical plane into a substantially horizontal plane, said roll being driven by the sheet passing thereover, means for rotatably supporting said roll adjacent its opposite ends, and braking means associated with the roll for retarding the free rotation thereof.

6. In apparatus for forming sheet glass, means for drawing the sheet upwardly, a freely rotatable roll for deflecting the sheet from a substantially vertical plane into a substantially horizontal plane, said roll being driven by the sheet passing thereover, means for rotatably supporting said roll adjacent its opposite ends, and a friction brake carried by the roll and acting as a yielding hold-back to the free rotation thereof.

7. In apparatus for forming sheet glass, means for drawing the sheet upwardly, a freely rotatable roll for deflecting the sheet from a substantially vertical plane into a substantially horizontal plane, bearing brackets for supporting the roll adjacent its opposite ends, braking means including a pair of semi-circular brake bands fitting about said roll, means for connecting the brake bands together, and means for normally urging the brake bands into engagement with the roll.

8. In apparatus for forming sheet glass, means for drawing the sheet upwardly, a freely rotatable roll for deflecting the sheet from a substantially vertical plane into a substantially horizontal plane, bearing brackets for supporting the roll adjacent its opposite ends, braking means including a pair of semi-circular brake bands fitting about said roll, means for connecting the brake bands together, and spring means carried by the bearing bracket at the corresponding end of the roll and engaging the brake bands for normally urging the bands into engagement with said roll.

9. In apparatus for forming sheet glass, means for drawing the sheet upwardly, a freely rotatable roll for deflecting the sheet from a substantially vertical plane into a substantially horizontal plane, bearing brackets for supporting the roll adjacent its opposite ends, braking means including a pair of semi-circular brake bands fitting about the roll, means for connecting the brake bands together at one end, spring means car-

ried by the bearing bracket at the corresponding end of the roll and engaging the opposite ends of the brake bands for normally urging the bands into engagement with said roll, and means for varying the pressure of said spring means upon the brake bands.

Signed at Charleston, in the county of Kanawha and State of West Virginia, this 12th day of November, 1930.
